UNITED STATES PATENT OFFICE.

ALBERT G. THOMPSON, OF MYSTIC RIVER, CONNECTICUT.

BOLT FOR DOORS.

SPECIFICATION forming part of Letters Patent No. 271,001, dated January 23, 1883.

Application filed September 25, 1882. (Model.)

To all whom it may concern:

Be it known that I, ALBERT G. THOMPSON, a citizen of the United States, residing at Mystic River, in the county of New London and State of Connecticut, have invented a new and useful Bolt for Doors, &c., of which the following is a specification, reference being had to the accompanying drawings.

Figure 1 is a front view. Fig. 2 is a sectional view on the line *x x*, and Fig. 3 is a sectional view on the line *y y*.

Corresponding parts in the several figures are denoted by like letters of reference.

This invention relates to an improved burglar-proof bolt for doors, &c., the construction and operation of which will be hereinafter more fully described, and particularly pointed out in the claim.

In the drawings hereto annexed, A represents the bolt, which slides in the shell B, which latter is cast with lugs C for attachment to the door D.

E is a back or bottom plate fitted in the shell or casing A, and having a lug or stud, F, projecting forwardly into a groove, G, in the rear side of bolt A.

H is a coiled spring placed in groove G and bearing against the stud F, thus serving to force the bolt A automatically into the shell or casing B. Bolt A is manipulated by means of a handle consisting of a set-screw, I, projecting through a slot, J, in the casing, and having a flange, K, bearing against the latter. By tightening said set-screw the bolt A may be

secured in any position to which it may be adjusted. 35

L is the receiving shell or cap, which is cast or formed with lugs M, by which it is attached to the door-post N. A back or bottom plate, O, suitably secured to the cap L, has a spring-40 catch, P, the handle of which, Q, projects through a notch in the end of cap L, and which is provided with a tooth, R, adapted to engage a notch, S, in the under side of the front end of bolt A.

The operation of my invention will be readily understood. When the bolt A is pushed out it engages the spring-catch P, by which it is held in a locked position, preventing it from being picked or opened from the outside. It 50 may, in addition, be made fast by tightening the set screw handle I.

I claim and desire to secure by Letters Patent of the United States—

The combination of the casing B, bolt A, having spring H, adapted to force it back into said casing, and provided with a notch, S, the set-screw I, forming a handle for said bolt, and the receiving-cap L, having spring-catch P, provided with projecting handle Q, and tooth R, 60 as and for the purpose set forth.

In testimony that I claim the foregoing as my own I have hereto affixed my signature in presence of two witnesses.

ALBERT GAINS THOMPSON.
